DESIGN FOR A GRAVE MARKER

Robert S. Hammond, Woodbury, N. J.

Application January 15, 1945, Serial No. 117,430

Term of patent 14 years

(Cl. D79—2)

To all whom it may concern:

Be it known that I, Robert S. Hammond, a citizen of the United States, residing at Woodbury, in the county of Gloucester, and State of New Jersey, have invented a new, original, and ornamental Design for Grave Marker, of which the following is a specification, reference being had to the accompanying drawing, forming part thereof, in which

Fig. 1 is a front elevation of a grave marker, showing my new design; and

Fig. 2 is a sectional view taken on the line 2—2 of Fig. 1.

The essential and characteristic features of the design are shown in full lines in the drawing.

I claim:

The ornamental design for a grave marker, as shown and described.

ROBERT S. HAMMOND.
